UNITED STATES PATENT OFFICE.

FRANK B. COOK, OF CHICAGO, ILLINOIS.

THERMAL PROTECTOR AND ALARM.

No. 815,006.

Specification of Letters Patent. Patented March 18, 1906.

Application filed December 18, 1902 Serial No. 135,677.

To all whom it may concern:

Be it known that I, FRANK B. COOK, a citizen of the United States of America, and a resident of Chicago, Cook county, Illinois, have invented a certain new and useful Improvement in a Thermal Protector and Alarm, of which the following is a specification.

My invention relates to apparatus for protecting electrical circuits and instruments against the intrusion of abnormally large or strong currents.

It relates more particularly to apparatus of this character in which heat-coil devices and carbon lightning-arresters are employed in conjunction with each other, so as not only to protect the circuits and instruments against lightning discharges or high potential currents, but also against the intrusion of currents only slightly in excess of normal, sometimes called "sneak-currents."

Generally stated, the object of my invention is to provide a simple, comparatively cheap, and highly efficient protector for electrical circuits.

A special object of my invention is to provide an improved alarm-circuit whereby each heat-coil when operated by excessive current will cause a local alarm to be sounded.

It is also an object to provide certain details and features of improvement tending to increase the general efficiency and service ability of a protector of this particular character.

To the foregoing and other useful ends my invention consists in matters hereinafter set forth and claimed.

In the accompanying drawings, Figure 1 is a side elevation of a portion of my improved protective apparatus. Fig. 2 is an end elevation of the devices shown in Fig. 1. Fig. 3 is a vertical section on line 3-3 in Fig. 1. Fig. 4 is a diagram of my improved alarm-circuit. Fig. 5 is an enlarged detailed sectional view of one of the heat-coil devices.

Both the heat-coils A and the carbon lightning-arrestors B are arranged in rows or banks upon opposite sides of the metal plate or support C. This plate or support can be of any suitable or desired length, according to the number of heat-coils and carbon lightning-arresters which it may be desirable to support thereon. The means for separating these well-known protective devices consists, preferably, of a lower row of rods of insulation D, which are inserted transversely

through openings in the metal plate C. These rods are preferably provided with metallic cores d, which, as will be observed, are provided with a number of nuts d'. 60

My improved protective apparatus can be employed for any desired purpose. For example, it may be employed in connection with telephone-exchanges for the purpose of protecting the switchboard apparatus against excessive current. In such case the line-springs E and F are preferably insulated from the cores d, while the switchboard-springs G are electrically connected with said cores. The switchboard-springs H at the other side 70 can be insulated from these cores. The line-terminal e can be part of the line-spring E, while the other line-terminal f can be electrically connected with the line-spring F through the medium of a metallic sleeve f'. The switchboard-terminal h can be part of the switchboard-spring H, while the other switchboard-terminal g can be electrically connected with the switchboard-spring G through the medium of the core d. It will be understood 80 that this is the arrangement and construction adopted for each of the rods D. With this arrangement the cylindric heat-coil devices A, which are preferably provided with grooved heads, can be removably applied to 85 the notched upper ends of the line and switchboard springs. Thus the line and switchboard springs are arranged in pairs, each pair consisting of one line-spring and one switchboard-spring and the members of each 90 pair being normally held under tension by a cylindric heat-coil device. In this way all currents traversing the line-circuits are compelled to pass through the heat-coil devices, and consequently the latter are capable of 95 opening a circuit upon the intrusion of a current only slightly in excess of normal.

The heat-coil devices can be of any suitable or approved construction, but are preferably of the form or character shown in Fig. 5. In this figure it will be seen that the two metallic heads a and a' are connected through the medium of the two stem portions a² and a³ and the intervening solder or other fusible material a⁴. The end of the tubular stem portion a² is preferably insulated from the head a by a mass of insulating material a⁵. A heating-coil a⁶ is preferably wrapped around the two stem portions thus connected by the fusible material, one terminal of this coil being connected with the head a, while the other terminal is connected with the tu-

2

bular stem a^2 . Thus the separable conductor and solder, the heating-coil, and two heads are all connected in series. Now upon the passage of a current above the normal the heating-coil a^3 will develop sufficient heat to melt the solder a^4 , thereby allowing the tension of the line and switchboard springs to pull the sectional conductor apart. This of course disrupts or opens the circuit, preventing the passage of the excessive current to the switchboard apparatus. In addition to thus disrupting a circuit upon the passage of an abnormally large current, the heat-coil devices are capable of establishing a connection to ground. For example, each line-spring can be provided with contacts e' and f^2 , adapted to make contact with the brass mounting-strip b when the said springs are released by the breaking or giving way of the connections in the heat-coil devices. As the metallic plate or support C is preferably grounded at X , the abnormally large current is then afforded a conducting-path to ground. Thus each heat-coil, in addition to being capable of opening a line-circuit upon the encroachment of a dangerous current, is also adapted to connect the line with a conductor which leads to ground.

In order that the attendant may know when a heat-coil is operated or burned out, each heat-coil device is associated with means for closing the circuit of a local alarm. This is preferably accomplished by separating the pairs of line and switchboard springs by means of rods I , which are of rubber or other insulating material and which are inserted through openings in the metallic plate C . The opposite end portions of these insulating-
rods I are connected by metallic rods i . Auxiliary line-springs e^2 and f^3 are associated with the said line-springs and arranged in position to be normally held out of contact with the said metallic rods. The local alarm J and the battery j can be connected in series, and the normally open circuit can terminate at one end in the rod i and at the other end in the metallic plate C . With this arrangement the circuit of the local alarm is normally open—that is to say, is open while the heat-coils are all in place and in their normal condition—but when one of these heat-coil devices is operated by the passage of an excessive current then the released line-spring moves toward the plate C , carrying the auxiliary line-spring with it. The auxiliary line-spring then making contact with the metallic rod i serves to close the circuit of the local alarm, thereby causing a signal to be given. Thus the said local circuit when closed includes the metal plate C and the line-spring, the latter when released being electrically connected with the said plate through the medium of its contact. This circuit arrangement is simple and prevents crossing of the circuits. Furthermore, it

will be seen that it only necessitates the use of one metallic contact-rod at each side.

The carbon lightning-arresters B can be of the well-known type or construction, in which each arrester consists of a pair of carbon blocks b' , separated by a mica or other dielectric b^2 . Each pair of blocks, with the interposed dielectric, is preferably held in place by a second auxiliary line-spring e^3 or f^4 , as the case may be. Thus one block of each pair is electrically connected with the line, while the other block of each pair is connected with the grounded plate or support C . Consequently a lightning discharge or other high-potential current will be conducted from the line to ground through the medium of one of the lightning-arresters, the current arcing across from one carbon block to the other in the well-known manner. Thus the plate C is adapted to form part of both the local alarm-circuit and the connection to ground.

What I claim as my invention is—

1. A protector, comprising a flat metal plate, heat-coil devices mounted at each side of said plate, carbon lightning-arresters mounted along the edge of said plate, and a local alarm-circuit having a plurality of normally open switch-points in series adapted to be closed by the operation of any one of said heat-coil devices, said metal plate forming part of said local alarm-circuit and each heat-coil device having a line-spring adapted when released to constitute part of the alarm-circuit.

2. A protector, comprising a flat metal plate, heat-coil devices suitably mounted at each side of said plate, carbon lightning-arresters mounted along the edge of said plate, a conductor connecting said plate with ground, and a local alarm-circuit having a plurality of normally open switch-points in series adapted to be closed by the operation of any one of said heat-coil devices, said plate serving as part of both the alarm-circuit and the connection to ground, and the ground-circuit including one of said switch-points and each heat-coil device having a line-spring adapted when released to constitute part of the alarm-circuit.

3. A protector, comprising a metal support, heat-coil devices suitably mounted on said support, and a local alarm-circuit having a plurality of normally open switch-points in series adapted to be closed by the operation of any one of said heat-coil devices, said metal support serving as a part of said local alarm-circuit and each heat-coil device having a line-spring adapted when released to constitute part of the alarm-circuit.

4. A protector, comprising a flat metal plate, rods of insulation inserted through said plate, line and switchboard springs mounted on said rods, heat-coil devices removably applied to the ends of said springs, and a local

- alarm-circuit having a plurality of normally open switch-points in series adapted to be closed by the operation of any one of said heat-coil devices, said metal plate, and also 5 each of said line-springs, being adapted to form part of said local alarm-circuit and each heat-coil device having a line-spring adapted when released to constitute part of the alarm-circuit.
- 10 5. A protector, comprising a metal support, line and switchboard springs mounted on said support and insulated therefrom, heat-coil devices removably applied to the ends of said springs, and a local alarm-circuit 15 having a plurality of normally open switch-points in series adapted to be closed by the operation of any one of said heat-coil devices, said metal support, and also each of said line-springs being adapted to serve as a part of 20 said local alarm-circuit.
- 25 6. A protector, comprising a flat metal plate, line and switchboard springs mounted upon said plate and insulated therefrom, a single metallic contact-rod mounted at each side of said plate and insulated therefrom, auxiliary line-springs normally held out of contact with said metallic rods, heat-coil devices removably applied to the ends of said line and switchboard springs, and a local 30 alarm-circuit adapted to be closed by the operation of any one of said heat-coil devices, the said metallic contact-rods, and also the said line and auxiliary springs being adapted to serve as a part of said local alarm-circuit.
- 35 7. A protector, comprising a flat metal plate, line and switchboard springs mounted upon said plate and insulated therefrom, metallic contact-rods mounted upon the said plate and also insulated therefrom, auxiliary 40 line-springs normally held away from said metallic contact-rods, heat-coil devices removably applied to the ends of said line and switchboard springs, and a local alarm-circuit adapted to be closed by the operation of 45 any one of said heat-coil devices, said metal plate and also said line and auxiliary springs and metallic contact-rods being adapted to serve as a part of said local alarm-circuit.
- 50 8. A protector, comprising a flat metal plate, line and switchboard springs mounted upon said plate and insulated therefrom, two auxiliary line-springs associated with each line-spring and electrically connected with the latter, carbon lightning-arresters normally held in place on said metal plate by certain of said auxiliary line-springs, metallic contact-rods normally out of contact with the other of said auxiliary line-springs, heat-coil devices removably applied to the ends of 55 said line and switchboard springs, a conductor connecting the said metal plate with ground, and a local alarm-circuit adapted to be closed by the operation of any one of said heat-coil devices, said local alarm-circuit including said metal plate, and each of the said 60
- 65

auxiliary line-springs which are held normally away from said contact-rods being adapted to serve as part of said local alarm-circuit.

9. In a protector, a heat-coil device, comprising the heads a and a' , the mass of insulation a^3 , the tubular stem a^2 having one end buried in this mass of insulation, the inner stem a^3 electrically connected with the head a' and inserted in the said tubular stem, the solder a^4 for uniting said stems, and the heating-coil a^6 wrapped around said stems, the solder and heating-coil being connected in series.

10. In a device of the character described, 80 the combination of a metallic support, an inner line-spring and an outer switchboard-spring suitably mounted on said support, a heat-coil device removably applied to the ends of said springs, a normally open ground-circuit including said support and inner spring, and a normally open alarm-circuit including said support and inner line-spring.

11. In a device of the character described, 90 the combination of a metallic support, an inner line-spring and an outer switchboard-spring suitably mounted on said support, a heat-coil device removably applied to the ends of said springs, a normally open ground-circuit including said support and one of said 95 springs, and a normally open alarm-circuit including said support and said inner line-spring.

12. In a device of the character described, 100 the combination of a metallic support, an inner line-spring and an outer switchboard-spring suitably mounted on said support, a heat-coil device removably applied to the ends of said springs, a normally open ground-circuit including said support and one of said 105 springs, and an alarm-circuit normally open at two points and including said support and line-spring.

13. In a device of the character described, 110 the combination of a metallic support, line and switchboard springs suitably mounted on said support, a heat-coil device suitably applied to said springs, and an alarm-circuit normally open at a plurality of points and including said support and line-spring.

14. In a device of the character described, 115 the combination of a metallic support, an electrothermal cut-out suitably mounted on said support, said cut-out including a line-spring, and an alarm-circuit normally open 120 at a plurality of points and including said support and line-spring.

15. A thermal protector and alarm apparatus, comprising a metal support, line and switchboard springs mounted in pairs at each side of said support, suitable heat-coil devices applied to the ends of said pairs of springs, line-terminals connected with the line-springs and all mounted at one side of said support, switchboard-terminals connected with the 125 130

switchboard-springs and all mounted at the other side of said support, a normally open ground-circuit including said support, each line-spring when released being adapted to 5 constitute part of said ground-circuit, and a normally open alarm-circuit, each line-spring when released being also adapted to constitute part of the alarm-circuit.

16. A thermal protector and alarm apparatus, comprising a metal support, line and switchboard springs suitably mounted on said support, suitable heat-coil devices applied to said springs to normally hold them under tension, a normally open ground-circuit including said support, each line-spring when released being adapted to constitute 15 part of said ground-circuit, and an alarm-circuit normally open at two points, each line-spring when released being adapted to also 20 constitute part of said alarm-circuit.

17. A thermal protector and alarm apparatus, comprising a metal support, line and switchboard springs mounted on said support, suitable heat-coil devices applied to the 25 said springs to normally hold the same under

tension, a normally open ground-circuit including said support, each line-spring when released being adapted to constitute part of the said ground-circuit, and an alarm-circuit normally open at two points and including 30 said support, each line-spring when released being also adapted to constitute part of the said alarm-circuit.

18. In a device of the character described, the combination of a metallic support, line 35 and switchboard springs mounted in pairs at each side of said support, heat-coil devices suitably applied to said springs, a normally open alarm-circuit including the line-springs, line-terminals connected with the line-springs 40 and all mounted at one side of said support, and switchboard-terminals connected with the said switchboard-springs and all mounted at the other side of said support.

Signed by me at Chicago, Cook county, 45 Illinois, this 11th day of December, 1902.

FRANK B. COOK.
